DESIGN FOR A LICENSE HOLDER KEY CHAIN WITH FRONT ACTION PENCIL TIP

Martin E. Trollen, St. Paul, Minn., assignor to
Brown & Bigelow, St. Paul, Minn., a corpora-
tion of Minnesota

Application November 27, 1944, Serial No. 116,564

Term of patent 14 years

(Cl. D17—14)

To all whom it may concern:

Be it known that I, Martin E. Trollen, a citizen of the United States, residing at St. Paul, county of Ramsey, and State of Minnesota, have invented a new, original, and ornamental Design for a License Holder Key Chain with Front Action Pencil Tip, of which the following is a specification, reference being had to the accompanying drawing, forming part thereof.

Fig. 1 is a side elevational view of a license holder key chain with front action pencil tip, showing my new design; and

Fig. 2 is an end view on the line 2—2 of Fig. 1 with the chain omitted.

I claim:

The ornamental design for a license holder key chain with front action pencil tip, as shown.

MARTIN E. TROLLEN.
